METHOD AND MEANS FOR BURNING LIQUID FUEL IN FURNACES FOR HEATING
BUILDINGS

Application filed August 6, 1925. Serial No. 48,464.

The invention relates to an improved method of burning liquid fuel in connection with furnaces generally, and more especially in connection with steam or hot water boilers 5 or hot air furnaces used for heating homes, or other buildings and to an apparatus for practicing said process.

In the burning of liquid fuel, especially non-volatile or heavy hydrocarbons, the fuel 10 is either atomized wholly or in part or is vaporized, and is then mixed with air and with the air is forcibly discharged into an open combustion chamber, wherein it is ignited and burned. The combustion chamber 15 of the preferred modern construction is so formed with reference to the incoming mixture of air and of atomized or partially atomized or vaporized liquid fuel, that the flame is caused to swirl about in the combustion chamber in a substantially horizontal plane and to roll or wind upon itself within the combustion chamber so that the flame is practically confined therein until combustion 20 is practically complete. Such method 25 and combustion chamber are described in Letters-Patent No. 1,284,182 to Doble, November 5, 1918, and in a patent granted to the present inventor, No. 1,379,008, May 24, 1921.

It has been found in the operation of burners such as those described in the two patents referred to, that a very perceptible roaring noise is produced in the burning of the atomized liquid fuel, which in the case of lightly built or small houses has been more or less 35 objectionable. Again, on account of the intense heat produced in the metal combustion chamber, due to the fact that substantially complete combustion of all the fuel takes place in the combustion chamber, it has been 40 desirable to make the combustion chamber of special alloys which are expensive.

It has long been known that when an inert or neutral gas or a gas non-combustible with oxygen is introduced with the air supplied 45 to a furnace to support combustion of the fuel therein, the inert gas acts as a diluent of the air and delays combustion of the fuel. The flame, by reason of the dilution and delayed combustion, is expanded and lengthened 50 beyond the combustion chamber of the fur-

nace so as to render the heat of combustion effective in the region beyond the combustion chamber and the heat of the flame is not so intense in the vicinity of the combustion chamber itself as in the case where combustion is completed in the combustion chamber. Manifestly, however, the material surrounding and defining the passageways or flues in the regions beyond the combustion chamber must be raised to a temperature 55 which will promote combustion in said regions.

In the temperature producing apparatus and controlling means, therefor, described in my aforesaid Patent No. 1,379,008, the supply of air and fuel to the combustion chamber is intermittent and its initial ignition at the beginning of every interval during which the fuel is burned is thermostatically controlled. Anything that would in the beginning 65 delay combustion or reduce the heat of combustion in the combustion chamber would be highly objectionable in an apparatus of the kind. Again, any expansion of the flame and delay of combustion until the flame 70 reaches the flues of the boiler is impracticable, since contact with the relatively cold flues 75 would stop complete combustion and result in the formation of CO gas.

The object of the present invention is to provide a method and an apparatus whereby an inert diluent of the air may be introduced into the combustion chamber with the air and fuel during the process of combustion after initial ignition with air undiluted has taken 85 place and after the fuel has been brought to complete combustion, to thereafter somewhat retard combustion in the combustion chamber; and to do this without expanding or extending the flame to any considerable extent 90 beyond the confines of the combustion chamber into the neighborhood of the furnace flues wherein complete combustion and the production of unconverted CO gas would result. When an inert gas is used in this way in a 95 burner of the kind hereinabove referred to, I have found that the noise of combustion is materially reduced. Instead of the roaring white flame produced with air alone, the fuel burns with a lazy, purple or blue, substan- 100

tially noiseless flame which overflows the top of the burner. In addition the intense heating of the walls of the combustion chamber produced by burning the fuel with air alone, is appreciably reduced, so that cheaper metal 5 may be used for the combustion chamber. And finally, as shown by tests, a maximum per cent of CO_2 gas is produced by the flame burning in this manner.

A convenient diluent for the air and fuel 10 and the one generally used is provided by the products of combustion which may be taken from the furnace beyond the burner, preferably from the stack. In carrying out my invention, I lead by a conduit a small part of 15 the products of combustion from the stack and introduce them in proportions capable of adjustment with the fresh air which is normally drawn in and discharged by a fan into the combustion chamber, together with the atomized liquid fuel to be burnt. The supply 20 of the products of combustion is automatically controlled, so that in the beginning and prior to the initial ignition of the fuel, air alone is introduced into the combustion chamber 25 with the fuel and complete combustion in the combustion chamber as heretofore is allowed to continue for a predetermined time interval and until the fuel is burning at its maximum with complete or substantially 30 complete combustion in the combustion chamber.

The inert products of combustion are then introduced with the air to slow down or retard 35 combustion in the confines of the combustion chamber and the supply of the inert diluent is continued during the remainder of the interval in which fuel is supplied to the burner and until by operation of the thermostat or otherwise in a well-known manner, the supply of fuel and of the mixture of air and diluent is shut off and combustion ceases. The supply of inert gas is then cut off and in the intermittent period when no combustion 40 takes place, remains shut off until after liquid fuel and fresh air undiluted are again supplied to the burner, initially ignited, and brought to full combustion; whereupon the inert gas is again introduced with the air and the process takes place as first described.

Several different devices may be employed to control the supply of the products of combustion with the air and herein I have shown a thermostatic device, a pneumatic device and 55 an electric motor device, any one of which may be efficiently used for the purpose. Other devices may be used.

In illustrating the invention, I have shown it applied to an apparatus including a combustion chamber, a fan or blower for discharging air together with liquid fuel atomized by the air into the combustion chamber and an automatic control for starting the fan and igniting the combustible mixture in the 60 combustion chamber, substantially as illus-

trated and described in my aforesaid patent; but it will be understood that this is by way of illustration only and not by way of limitation, as the invention is designed for use in connection with any automatically controlled 70 temperature producing means burning liquid hydrocarbon fuel, to which it may be applied.

In the drawings:—

Figure 1 represents a side elevation of a familiar domestic furnace, with a liquid fuel combustion chamber mounted within the firebox and a liquid fuel atomizer automatically controlled for spraying liquid fuel mixed with air into said combustion chamber, such as described in my aforesaid patent, the same 75 being provided with an apparatus for introducing the products of combustion with the air in accordance with my invention.

Figure 2 is a detail view on an enlarged scale, partly in side elevation and partly in section, illustrating a thermostatically operated device for controlling the introduction of the products of combustion with the air supply to the combustion chamber.

Figure 3 is a view representing a section 80 through Figure 2, in a plane indicated by a line 3—3 of Figure 2.

Figure 4 is a top plan view of the air supply pipe, fan and combustion chamber with a pneumatically controlled member for the introduction of the products of combustion.

Figure 5 is a view representing a section 85 through Figure 4 in a plane indicated by a line 5—5 of Figure 4.

Figure 6 is a view representing a top plan 90 view of the fan, of the air supply pipe leading to the combustion chamber, and of the electric motor for closing and opening the switch in the fan motor circuit and for operating a gas valve controlling a pilot flame for 95 initially igniting the combustible mixture in the combustion chamber.

Figure 7 is a view representing a side elevation of the parts shown in Figure 6.

Fig. 8 is a perspective view of part of the 100 operating mechanism shown in Figs. 6 and 7.

Referring now to that embodiment of the invention illustrated in the drawings and particularly in Figures 1 to 3, inclusive:—10 indicates a furnace of any usual construction provided with a fire-box 11 and with a stack 12 through which the products of combustion are discharged. 13 indicates a combustion chamber, which in this case, is a heavy metal box-like structure adapted to confine the flame. 14 indicates an electric motor driven fan or blower, by means of which fresh air is normally discharged through a pipe 15 into the combustion chamber, said air acting in the example illustrated to atomize the liquid hydrocarbon fuel supplied by a pipe 16 from any convenient, suitably controlled source of supply prior to or as it is introduced into the combustion chamber 13. 43 indicates an electric motor, controlled by a thermostat or 115 120 125 130

other or auxiliary automatic control, not shown, which motor is adapted to close and open the switch in the circuit of the fan motor and to actuate the ignition device, as by opening and closing the valve supplying a pilot flame in the combustion chamber. Said parts of the apparatus are familiar and may be as described in the patent referred to and require no further illustration or description.

17 indicates a pipe or conduit of comparatively small cross-section which is adapted to introduce the inert gas, in this case a part of the products of combustion, along with the air into the fan casing, whence it is discharged with the fresh air through the pipe 15. The conduit 17, as illustrated, is connected in any suitable manner, as by a fitting 18 to the stack 12. The other end of said conduit is attached to a nipple 19 providing an inlet port to a valve casing 20 which opens by a passageway 21 into the casing of the fan or blower 14. Below the inlet nipple 19 on the diametrically opposite side of the valve casing 20 is an inlet port 22, for the admission of fresh air. An ordinary butterfly valve 23 is mounted in the valve casing 20 on a spindle or shaft 24 which projects at one end beyond the valve casing 20.

The butterfly valve 23, when in the position shown in full lines in Figure 3, cuts off the inlet opening for the products of combustion from communication with the passage way 21 into the casing 14 of the fan, and leaves said passageway fully open to the inlet 22 for the entrance of air. With the valve in this position, the operation of the fan will draw into and discharge through the pipe 15, fresh air only. When said valve 23 is shifted clockwise into the position shown in dotted lines at 23^a, the opening into the passageway 21, will be cut down or shut off on the side of the air inlet 22 and will be correspondingly opened on the side of the products of combustion inlet 19. Thus, in this position a certain definite proportion of the fluid discharged through the pipe 15 will be products of combustion and the balance will be air; and the proportion of the products of combustion to the air of the mixture will depend upon how far the valve 23 has been shifted clock-wise. Thus, by this means a positive control of the proportions of the products of combustion or inert gas, as compared to the air, is provided.

The rotative movement of the valve 23 may be limited in any convenient way. As shown in Figure 3, a bolt 23^b fixed in the cylindrical wall of the valve casing 20 is placed in the path of an end of the valve 23 at a point so that the valve will strike the bolt when the intended limit of movement of the valve is reached. The bolt is engaged in a slot 23^c in the valve casing wall with its head on the inside of the valve casing and a nut 23^d engaged against the outside periphery of said casing. By this construction the position of

the stop bolt may be varied to adjust the limit of opening movement of the valve and the resultant proportion of inert gas introduced with the air.

25 indicates a thermostatic element located in the fire-box 11 adjacent to the combustion chamber 13 and connected by suitable mechanism, now to be described, to the valve shaft 24, to operate the butterfly valve 23. Said thermostatic element is of familiar kind consisting of a ribbon or band comprising two strips of metal of different co-efficients of expansion arranged in a spiral coil about a rod or shaft 26. One end 25^a of the ribbon coil 25 is attached in any convenient manner to the rod 26. The rod 26 itself extends through a pipe 27 closed at its ends by bearing caps 28, 29, which are apertured to receive the rod 26. Said bearing caps are made integral with or attached to bracket arms 28^a, 29^a, respectively,—one of which, 29^a is attached to the shell of the combustion chamber and the other of which 28^a, is attached to the air discharge pipe 15. By thus mounting the parts, the thermostatic ribbon 25 is located in close vicinity to the combustion chamber and assumes the temperature thereof. The forward end 25^b of the thermostatic ribbon 25 is fixed to the bearing cap 29 and is thus made rigid and non-rotative with respect to the pipe 27. The rod 26 on the other hand is capable of rotative movement in the bearing caps 28, 29. Said rod extends into the neighborhood of the valve casing 20 where it has a crank arm 30 fixed to its end. A crank arm 31 is fixed to the butterfly valve shaft 24 and a link 32 connects the two crank arms 30, 31.

When in the operation of the apparatus the fan motor is started, fresh air is drawn in through the air port 22 and the passageway 21 (now in full communication with said air port) and discharged with the fuel oil atomized thereby through the pipe 15 into the combustion chamber 13 where the combustible mixture is instantly ignited by a pilot light or otherwise in a familiar manner. Combustion takes place with a white, hot flame which is substantially confined within the limits of the combustion chamber 13 as heretofore. As the combustion chamber heats up, the heat of its metal body is imparted to the thermostatic ribbon 25 and said ribbon slowly uncoils. The uncoiling of the ribbon, by thus causing the connection of its rear end 25^a to the rod 26 imparts a rotative movement to said rod in a clock-wise direction, as looked at in Figure 3. This rotative movement of the rod is communicated through the crank arm 30, the link 32 and the crank arm 31 to the butterfly valve 23 so as to shift said butterfly valve clock-wise from the position shown in full lines to a position at or near that shown in dotted lines 23^a in Figure 3.

Manifestly in this movement of the butterfly valve under the action of the thermostatic

ribbon, there will be admitted first a small and then a gradually increasing proportion of the products of combustion with the fresh air into the pipe 15 to be discharged thereby into the combustion chamber to dilute the combustible mixture until a predetermined opening for the butterfly valve, determined by the position of the stop bolt 23^b, has been reached,—whereupon further movement of the butterfly valve is arrested.

It has been found that upon the opening of the butterfly valve 23 to the predetermined limit, the flame, which until the beginning of the dilution of the air by the introduction of the products of combustion has been a white hot flame practically confined to the combustion chamber, enlarges or expands somewhat above the combustion chamber and becomes lazy and of a bluish or deep purple color somewhat simulating the appearance in this respect of the flame of a Bunsen burner, but without the forcible discharge of the flame of such burner. In addition, the objectionable noise of burning, evident in burners of the kind as heretofore constructed and operated with air alone, is almost entirely, if not absolutely eliminated,—the flame burning with a gentle purring which is hardly distinguishable when the furnace door is closed. And tests show a maximum percentage of CO₂ gas in the resultant products of combustion.

In addition, the heat of the flame in the combustion chamber, except at the beginning when the gas is first ignited and before the products of combustion are introduced, is considerably reduced and as the burning of the undiluted mixture is only required for the short time needed to ignite the flame and get it to its full capacity, it is possible to use cheaper metal in the construction of the combustion chamber.

In Figures 4 and 5, I have shown a modified form of the invention in which a pneumatic control for the introduction of the products of combustion into the air supply to the combustion chamber is used instead of the thermostatic control member hereinbefore described. In said views, like parts are indicated by the same numerals as used heretofore.

In this case, a diaphragm chamber 33 is connected with the air supply pipe 15 at some point intermediate the fan casing 14 and the burner 13. The diaphragm casing may be of any usual or familiar construction and is connected on one side by an apertured rod 34 with the air pipe 15. The rod 34 has a small bore 35 and has threaded laterally into it, a set screw 36, by means of which the effective cross-sectional area of said bore may be determined. 37 indicates the diaphragm in the casing. Said diaphragm is exposed on its side nearest the pipe 15 to the air pressure in the pipe 15 by reason of the connection of the diaphragm casing on that side of

the diaphragm with the pipe 15 through the bore of the pipe 34.

The diaphragm on its upper side has fixed to it a pin 38, which has suitable bearing for vertical movement in the upper side of the diaphragm casing, beyond which it projects to be pivoted at 39 to a lever 40. The lever 40 is fulcrumed to a stud 41 rising from the diaphragm casing on the side remote from the valve casing 20 and the other end of said lever 40 is connected by a link 42 to the crank arm 31.

The operation of the pneumatic control is as follows:—When air is discharged by the fan through the pipe 15 to begin combustion in the combustion chamber 13, pressure is built up in the pipe 15 and this pressure gradually builds up through the bore 35 of the rod 34 on the under side of the diaphragm 37. After a predetermined time limit, depending upon the effective cross-sectional area of the bore 35 as determined by the set screw 36, this pressure will have been built up far enough to lift the diaphragm 37 and through the pin 38 to operate the lever 40, so as to swing the valve 23 from the position shown in full lines in Figure 3 to the position shown in dotted lines 23^a therein, as heretofore described. Thus, the products of combustion are again introduced with the air supply after the lapse of a predetermined time interval from the initial ignition of the combustible mixture in the combustion chamber.

In Figures 6 and 7, still another modification of the invention is shown,—the control member being in this case the electric motor 43 which closes and opens a switch in the fan motor circuit and simultaneously opens and closes the valve to the pilot flame in the combustion chamber or operates other mechanism to bring other ignition means into play. Detailed description or illustration of the motor or of the parts operated thereby in the form of burner and ignition means herein illustrated are not necessary, since that or another motor device adapted to operate at the time the combustible constituents are ignited and shut off may be used.

As before like parts are indicated by the same numerals used in the beginning. 44 indicates the shaft of the motor 43. At the end of the motor shaft 44 is fixed a cam disc 45, having a cam projection 45^a. 46 indicates a rocking U-frame pivotally mounted at 47 on a fixed member 48 adjacent the end of the shaft 44 with said U-frame straddling the parts adjacent to its fulcrum 47 and has one leg 46^a in the plane of the cam disc 45 with its end engaged therewith. The other leg 46^b of said U-frame is the short arm of a bell crank lever 49. Said bell-crank lever is normally depressed by a weight 49^a so that the arm 46^a of the U-frame 46 is always held in engagement with the cam disc 45. A link 130

50 connects the lever 49 to the crank arm 31 of the butterfly valve shaft 24.

When the motor 43, by reason of the operation of the thermostat or other control is started into operation to close the switch in the fan motor circuit and to actuate the ignition device, the cam disc 45^a will rotate with the motor shaft 44 from the position shown in full lines in Figure 7 until the cam projection 45^a is brought into operative engagement with the end of the arm 46^a. This engagement with the arm 46^a will rock the U-frame 46 on its fulcrum 47 to swing the bell-crank lever 49 upwardly so as to lift the lever 49 and with it the link 50. This upward movement of the link 50 rotates the butterfly valve shaft 24 to move the butterfly valve 23 from the position shown in full lines in Figure 3 to the position shown in dotted lines 23^a therein, as before for admission of the products of combustion with the air. Thus the operation is again as heretofore described.

It will be understood that no matter how the control member which actuates the valve 23 is operated nor what may be the character of the elements by which it is brought into play, said control member must be so correlated with and adjusted to the operation of the devices which bring about the initial ignition and combustion in the combustion chamber, that the predetermined time interval will elapse before the valve is opened to admit the products of combustion with the air into the combustion chamber. This time interval is required in order that the temperature in the combustion chamber may be brought to that high degree which is necessary in order that there may be complete combustion of the fuel before the oxygen supply has been diluted by the products of combustion. In the absence of this high temperature there will be a failure of complete combustion when the oxygen supply has been diluted with the inert gas with a resultant formation of the deadly CO gas in large quantities which would escape unconsumed and would be highly dangerous in a furnace for heating domestic and other buildings.

The necessity for the elapse of this time interval during which the fuel is completely burnt with air alone until the required high temperature has been produced in parts of the structure in the neighborhood of which combustion is to take place, has been fully recognized where the products of combustion have been introduced with air to support combustion; but the problem in the present instance is to get the benefits described without expanding or dilating the flame beyond the immediate vicinity of the combustion chamber since it would be practically impossible to maintain in the flues of a boiler or furnace a temperature of said flues sufficiently high to promote complete combustion.

15 The ratio of the amount of products of

combustion to air in the diluted air injected with the fuel into the combustion chamber must be carefully determined for each kind of apparatus and size of combustion chamber. The said ratio may only be determined accurately by experiment and is then fixed by adjustment of the stop, namely the stop-bolt 23^b (Figure 3) or equivalent device which arrests the movement of the mixing valve 23.

In making this determination (after first disconnecting the mixing valve from the control member used for actuating it and after initial ignition has taken place and the flame has been brought to its maximum temperature of combustion) the valve 23 is moved to admit gradually increasing proportions of products of combustion, the change in the color of the flame and its expansion being noted. The proportion of products of combustion is increased until the flame materially quiets down, the noise of combustion substantially disappears and the flame burns with a purplish or blue color. Care must be used however not to expand the flame materially beyond the immediate vicinity of the combustion chamber or into contact with the boiler or furnace flues.

I have found that excellent results are obtained with a combustion apparatus of the kind herein illustrated and described including a burner of a capacity to burn approximately two gallons of fuel per hour where the products of combustion are from 15 to 20 per cent of the mixture of air and products of combustion injected into the combustion chamber.

While in illustrating and describing the invention I have shown an apparatus which contemplates preferably a complete atomization of the liquid fuel prior to or as it enters the combustion chamber, it will be understood that the invention is applicable, whether the fuel is completely atomized, atomized only in part or vaporized wholly or in part, either prior to its injection into the combustion chamber or at the instant it is injected into the combustion chamber or subsequent to its injection thereinto. The word fuel therefore as used in the claims is to be understood to cover and include liquid fuel when atomized, wholly or in part or vaporized, wholly or in part.

Again, the invention is not limited to use with a combustion chamber made of metal such as herein described, but contemplates a combustion chamber made of any material designed to produce substantially complete combustion of the fuel within the combustion chamber; and it also contemplates a combustion chamber of any suitable form or shape which may function as a flaming combustible confining means for the prompt production of high temperature conditions.

Such a combustion chamber or confining means may be an integral part of the oil burn-

er proper or may be built into the fire box of the ordinary heating boiler or furnace.

I claim as my invention:—

1. The method of burning liquid fuel in a confining combustion chamber, which consists in introducing all the combustion-supporting air and the fuel into said combustion chamber, igniting the mixture of fuel and air and swirling the burning mixture within the chamber with force to confine the burning mixture to the said chamber until combustion is practically complete; in thus burning the mixture with air alone for a period of time until combustion has developed to a maximum of temperature; and in then injecting with the air a neutral gas, non-combustible with air, said neutral gas and air being mixed in predetermined ratio adapted to somewhat delay combustion in said chamber and reduce the noise thereof, but without expanding the flame materially beyond the vicinity of said combustion chamber.

2. In a liquid hydrocarbon fuel burning apparatus, in combination with a flame confining combustion chamber, means for introducing a flame combustible including fresh air into said chamber, said combustion chamber being formed to produce a swirling movement of the burning combustible in the chamber, means for igniting said flame combustible, and an automatic control device for said introducing means, a valve casing, associated with said introducing means, said casing having an air inlet port and a second inlet port, a conduit adapted for leading an inert gas to said second inlet port, a mixing valve in said casing, said mixing valve normally closing off said second inlet port but being movable to a predetermined point for admitting said inert gas through that port in a predetermined ratio to the air admitted, and a valve control device adapted to move said valve to said predetermined point after combustion has been continued for a predetermined time interval.

3. In a liquid hydrocarbon fuel burning apparatus, in combination with a flame confining combustion chamber, means for introducing a flame combustible including fresh air into said chamber, said combustion chamber being formed to produce a swirling movement of the burning combustible in the chamber, means for igniting said flame combustible, and an automatic control device for said introducing means, a valve casing, associated with said introducing means, said casing having an air inlet port and a second inlet port, a conduit adapted for leading an inert gas to said second inlet port, a mixing valve in said casing, said mixing valve normally closing off said second inlet port but being movable to a predetermined point for admitting said inert gas through that port in a predetermined ratio to the air admitted, and an electrically operated valve control device

adapted to move said valve to said predetermined point after combustion has been continued for a predetermined time interval.

4. The method of burning liquid fuel in a furnace for heating buildings, which consists in introducing combustion supporting air and fuel into a combustion chamber located in said furnace, in igniting the mixture of fuel and air and bringing the same to substantially complete combustion in said combustion chamber; in thus burning the mixture with air alone until combustion has developed to a maximum of temperature; and in then injecting with the air a neutral gas, non-combustible with air, in a predetermined ratio to the air adapted somewhat to delay combustion in said chamber and reduce the noise thereof, but without expanding the flame materially beyond the vicinity of said combustion chamber.

5. The method of burning liquid fuel which consists in automatically introducing combustion supporting air with the fuel into a combustion chamber, automatically igniting the mixture of fuel and air and burning the same substantially within the chamber until the heat of combustion has developed to a maximum of temperature; and in then automatically injecting with the air a neutral gas, non-combustible with air, in a predetermined ratio to the air adapted somewhat to delay combustion in said chamber and reduce the noise thereof, but without expanding the flame materially beyond the vicinity of said combustion chamber.

6. In a liquid hydrocarbon fuel burning apparatus, in combination with a combustion chamber, means for introducing a flame combustible, including fresh air, into said chamber, means for igniting said flame combustible, and an automatic control device for said introducing means, a valve casing associated with said introducing means, said casing having an air inlet port and a second inlet port, a conduit adapted for leading an inert gas to said second inlet port, a mixing valve in said casing normally closing off said second inlet port, but movable to a predetermined point for admitting said inert gas through that port in a predetermined ratio to the air admitted, and an electrically operated valve control device adapted to move said valve to said predetermined point after combustion has been continued for a predetermined time interval.

In testimony that I claim the foregoing as my invention, I affix my signature this 31st day of July, 1925.

ALBERT B. FRENIER.
